UNITED STATES PATENT OFFICE.

WALTER H. BOWMAN, OF CHICAGO, ILLINOIS, ASSIGNOR TO GOLDSMITH BROS.
SMEILING & REFINING CO., OF CHICAGO, ILLINOIS, A CORPORATION OF
WEST VIRGINIA.

CONTAINER FOR MERCURY.

1,427,351.

Specification of Letters Patent. Patented Aug. 29, 1922.

Application filed February 1, 1922. Serial No. 533,271.

To all whom it may concern:

Be it known that I, WALTER H. BOWMAN, a citizen of the United States of America, and a resident of Chicago, county of Cook, 5 and State of Illinois, have invented a new and useful Improvement in Containers for Mercury, of which the following is a specification.

This invention relates to receptacles suitably designed for receiving mercury and for use in marketing the same, while being still further serviceable for dispensing the mercury in any desired amounts, for example, to meet the requirements of dental 15 surgeons.

The object of the invention is to protect the substance contained in the receptacle from contamination while the receptacle is still suitable for conveniently dispensing desired quantities of the substance contained 20 therein.

The objects of the invention are accomplished by the device shown in the drawing, wherein—

25 Figure 1 shows the improved container with its surrounding carton shown in section.

Fig. 2 is an enlarged vertical sectional view of the container.

30 At the present time mercury is retailed in small jars or bottles, and with the better grades of mercury such as used in the dental profession, considerable care must be exercised to prevent contamination or oxidizing

35 of the mercury, but the usual jars or bottles in which it is sold do not have any provision for accurately dispensing the mercury as needed, and, therefore, it is customary for the dental surgeon to be provided with a

40 dispensing receptacle within which part of the mercury is poured. It is the purpose of the present invention to provide a suitable container for the mercury both for marketing purposes and for the needs of dental

45 surgeons. With this end in view, the container is provided with a specially designed stopper and double seating valve whereby a finely adjusted outlet may be afforded by slightly unscrewing the cap of the stopper

50 so that a fine stream of mercury may be poured from the container.

The structure as illustrated shows a glass bottle having a body 1 and reduced neck portion 2. This neck portion has an exterior thread 3 for receiving a centrally

apertured cover 4. The purpose of this cover is to retain the stopper 5 in the neck of the bottle against the pressure of the weight of the mercury therein when the bottle is tipped to pour mercury therefrom. 60 The stopper 5 has a central axial opening 6 within which fits a tubular member 7 having an annular shoulder 8 above the upper edge of the stopper and in position to be engaged by the locking cover 4. The upper end of 65 the tubular member 7 is threaded to receive the nipple or cap 9. This cap is hollow to provide a passage 10 for the mercury, and at its upper end has a perforation or outlet 11. A valve 12 fits within the space 10 of 70 the cap 9 and has a reduced portion or stem 13 extending downwardly into the tubular member 7. This portion 13 is of less diameter than the bore of the tubular member 7, and likewise a similar stem 14 extending 75 upwardly from the valve is of less diameter than the diameter of the axial recess 15 in the cap. The stem 14 seats against the cap at the aperture 11 and the shoulder 16 at the enlarged part of the valve seats on the 80 upper edge of the tubular member 7.

Due to the weight of the mercury it is necessary to carefully protect the receptacle when in transit, and for this reason the carton 17 within which it is packaged is provided with a tubular spacer 18, surrounding the neck of the receptacle and extending from its shoulder 19 to the cap 20 of the 85 carton.

In the use of the receptacle in dispensing 90 some such substance as mercury, the cap 9 is unscrewed more or less in order to provide a passage of the desired size around valve 12. The valve floats on the mercury as the latter runs out around the valve. The 95 recess 15 in the cap being tapered toward the upper end of valve stem 14 provides a minute outlet for the mercury, and, therefore, prevents the mercury from flowing out faster than desired. This form of stopper serves to properly seal the receptacle, preventing contamination of the mercury or its oxidation, and also provides for accurately dispensing the mercury.

I claim:

1. A receptacle of the class described comprising an open-mouthed body, a stopper having a central aperture, a tubular element fitting said aperture and provided with a shoulder above the stopper, a cover having 110

105

110

threaded engagement with the receptacle and arranged to engage the shoulder on said tubular element, a hollow cap having threaded engagement with the upper end of 5 said tubular element, said cap being provided with a perforation, and a valve in said cap adapted to seat at both the said perforation in the cap and at the end of said tubular element.

10 2. A receptacle of the class described comprising an open-mouthed body, a stopper having a tubular extension affording an

outlet, a cap in threaded engagement with said tubular outlet, said cap having a perforation, and a valve in said cap, a seat for 15 the valve on said tubular outlet, and a seat for the valve on the cap at its perforation, said valve having an axial projection extending into said tubular element, but of less diameter than the bore of said tubular element. 20

Signed at Chicago this 2nd day of December, 1921.

WALTER H. BOWMAN.
